UNITED STATES PATENT OFFICE.

WILLIAM J. DAVIDSON, OF BIG SPRING, VIRGINIA.

PLOW AND CULTIVATOR.

SPECIFICATION forming part of Letters Patent No. 231,701, dated August 31, 1880.

Application filed February 7, 1880.

To all whom it may concern:

Be it known that I, WILLIAM J. DAVIDSON, of Big Spring, Montgomery county, Virginia, have invented Improvements in Plows and 5 Cultivators, of which the following is a specification.

My invention is an improvement in plows and cultivators, whereby to facilitate the attachment of one or more plow-standards to 10 and their adjustment on a single plow-beam, and to secure the lateral and angular adjustment of the standards and fasten them securely after adjustment and maintain the draft-line central with the plows.

15 In the drawings forming a part of this specification, Figure 1 is a perspective view of my improved cultivator-plow. Fig. 2 is a rear end view; Fig. 3, a plan, and Fig. 4 a side view of part of the plow.

20 H represents the plow-beam, which is provided with the usual handles J J, and with two arms, A A', projecting laterally to the same side, the arm A' being the longest, and being perforated to receive two clamp-bolts, 25 a a, which extend through slots b in an L-shaped bracket, B, which the bolts secure adjustably to the arm A'. To a slot, or to a series of holes, c, in the arm A, is adapted a draft-hook, C, which is secured adjustably by 30 a nut.

D is a bracket, which I construct preferably in the form of a yoke, secured to the beam H. In the bar f of the bracket D is a bolt-hole for the reception of the pivot-bolt i of the 35 cultivator-standard E, which, in this instance, is curved, one end being pointed or carrying the blade I, and the other having a slot, m, which is at an angle to a slot, n, in the bar f, as best shown in Fig. 4. The crossed slots m 40 n, where they coincide, present an opening for the passage of the bolt t, by which the standard may be clamped to the bar and secured after being adjusted to any desired angle.

It will be seen that the angle of the standard may be altered without removing the bolt t, after merely loosening the latter, but that when the bolt is adjusted in any position the pressure upon the standard has no tendency to displace it, so that a nice adjustment is se-

cured with but little strain on the bolt or liability to slip. 50

The bracket B has a slot, n, and is perforated to receive the pivot-bolt i of a second standard, E, which has a slot, m, and is secured and adjusted on the bracket B in like 55 manner as the first-named standard is on the bracket D.

The bracket B may be laterally adjusted after loosening the bolts a a, so as to vary the lateral distances between the plow-standards, 60 and the draft-hook C may be adjusted in the opening or openings c, so as to be always on the line midway between the standards, that the plow will pull evenly. When the standards are not laterally adjustable the adjustment of the hook C is not essential. 65

When but one blade is to be used the bracket B may be removed and replaced in the position shown in dotted lines, Fig. 3, and the standard or a colter then bolted to either side; 70 or a colter or plow-standard may then be secured directly to the plow-beam in front of that on the bracket B by means of a clip or clamp-bolt passed through a slot, s, in the beam adapted to receive it. It will be apparent that this standard may be secured directly to the beam H instead of to the bracket D, in which case the slot n is made in the beam or the slot s used to receive the bolt t. 75

I claim—

1. The combination of the plow-beam H, having the lateral arm A', the L-shaped bracket B, secured adjustably to the arm A', and adapted to be attached in different positions, and a standard, E, carried by the bracket B, substantially as herein set forth. 80

2. The combination of a curved standard, E, turning on a fixed pivot, i, and having a slot, m, the plow-beam or bracket, having a slot, n, crossing the slot m, and the adjustable bolt t, passing through both slots, as herein specified, for the purposes set forth. 85

In testimony whereof I have signed my name to this specification in the presence of two subscribing witnesses.

Witnesses: W. J. DAVIDSON.
